UNITED STATES PATENT OFFICE

JULIUS KAHN AND HERBERT E. WHITE, OF YOUNGSTOWN, OHIO, ASSIGNORS TO
TRUSCON STEEL COMPANY, OF YOUNGSTOWN, OHIO, A CORPORATION OF MICHIGAN

LATH STRUCTURE

Application filed February 11, 1929. Serial No. 339,085.

The object of the present invention is to provide as an article of manufacture, a lath structure for walls, ceilings and the like that will constitute an effective support and backing for the plaster, and while providing for the proper keying of the plaster material, will reduce the amount of such material necessary to a minimum, while producing a satisfactory wall structure.

10 In the accompanying drawings:

Figure 1 is a front elevation of a portion of a lath structure made in accordance with the present invention.

15 Figure 2 is a sectional view on the line 2—2 of Figure 1.

Figure 3 is a perspective view of a portion of the lath structure with the plaster in place thereon.

20 Figure 4 is a vertical sectional view on the line 4—4 of Figure 1.

Figure 5 is a detail perspective view of one of the staples showing its application.

25 Figure 6 is a rear elevation illustrating a staple after it has been clinched.

30 In the embodiment disclosed, a backing sheet 7 is employed. Preferably this sheet is made up of a number of plies of material, and consists of a backing ply 8 that is relatively heavy and rigid, so that it constitutes the main body of the sheet.

35 There is a facing sheet 9 of material light in weight and these two sheets are secured together by an interposed waterproof layer 10 that not only constitutes the adhesive between the two outer plies, but acts to prevent moisture from the wet plaster reaching the rear supporting ply 8.

40 The sheet 7, as a whole, is provided with rows of elongated depressions 11, the open sides of which are on the side of the sheet having the light facing material 9. As will be clear by reference to Figure 1, these depressions or pockets 11 are arranged so that those in each row are disposed end to end and those of one row are staggered with relation to those of the next. As a consequence the sheet is stiffened against bending transversely of the pockets, that is to say the walls of the pockets constitute sectional reinforcing ribs, and by the overlapping relation the

section of one rib bridges the space between the ends of the sections of the others.

45 Located on the outer face of the backing sheet, to-wit, that face carrying the light ply 9, are wires or rods which we term lath rods. These are designated 12. Each rod 12 extends longitudinally along and over the pockets of one of the rows and is fastened by staples 13 located between the ends of the adjacent pockets, the staples being driven through the backing sheet and having prongs 14 that are clinched beside each other as shown in Figure 6.

50 This structure is nailed or otherwise fastened to the usual studding, and plaster as 15 (see Figure 3) is then applied. By reason of the fact that the rods preferably lie directly against the backing sheet, a relatively thin coat of plaster is sufficient and at the same time effective keys are secured by the 55 plaster entering the pockets 11 and surrounding the portions of the rods that extend over the same. More than that the plaster that enters the pockets forms thereby short reinforcing ribs on the rear of the plaster body 60 and these ribs being staggered act as stiffeners for the plaster layer and indeed for the complete wall structure. A further and very material advantage resides in the employment of depressions as distinguished 65 from openings, particularly with the multiply backing sheet, as disclosed for the reason that the moisture from the wet plaster is prevented from getting to the rear or supporting ply because of the waterproof material 10. The backing and main supporting 70 ply 8 therefore does not become soggy and weakened by the liquid. The facing sheet 75 is employed to provide a satisfactory bonding material for the plaster.

80 From the foregoing, it is thought that the construction, operation and many advantages of the herein described invention will be apparent to those skilled in the art without further description and it will be understood that various changes in the size, shape, proportion, and minor details of construction may be resorted to without departing 85 from the spirit or sacrificing any of the advantages of the invention.

What we claim, is:

1. A plaster supporting structure comprising a backing sheet having elongated depressions forming open sided elongated pockets in one side of the sheet, and lath rods located outside the sheet and secured to the sheet and extending longitudinally over the open sides of the pockets.
2. A plaster supporting structure comprising a backing sheet having rows of spaced apart elongated depressions, the depressions of one row being staggered with respect to adjacent rows, forming open sided elongated pockets in one side of the sheet, and lath rods located outside the sheet and secured to the sheet and extending longitudinally over the open sides of the elongated pockets.
3. A plaster supporting structure, comprising a backing sheet having spaced elongated open pockets, lath rods located outside the sheets and extending along the face of the sheet and longitudinally over the elongated pockets, and fastening means located between the ends of the elongated pockets and securing the rods to the sheets.
4. A plaster supporting structure, comprising a backing sheet having rows of elongated open pockets, the pockets in each row being arranged end to end and spaced apart and the pockets of the different rows being staggered and bridging the spaces between the pockets of the adjacent rows, lath rods located outside the sheet and extending along the face of the sheet and longitudinally over the elongated pockets, and fastening means located between the ends of the pockets of the rows and securing the rods to the sheets.
5. A plaster supporting structure, comprising a backing sheet, said sheet comprising a body ply, a waterproof layer covering the same and a facing surface ply covering the waterproof layer for bonding with the plaster, said backing sheet having depressions that are open at said facing surface, and lath rods over said face and extending across the depressions.
6. A plaster supporting structure comprising a backing sheet, said sheet comprising a body ply, a lighter facing ply for bonding with the plaster and a waterproof ply between the said plies and uniting them, said backing sheet having depressions that open at the facing surface, and lath rods over said facing surface and extending across the depressions.
7. A plaster supporting structure comprising a backing sheet, said sheet comprising a body ply, a lighter facing ply for bonding with the plaster, and a waterproof ply between the said plies and uniting them, said backing sheet having rows of elongated depressions that include all of said plies and open through the front face of the sheet, the depressions of each row being located lengthwise in the row and spaced apart and the de-

pressions of one row being staggered with respect to adjacent rows, lath rods extending longitudinally along the rows and located lengthwise over the elongated open sides of the depressions, and fasteners securing the rods to the backing sheet.

8. A wall structure comprising a backing sheet having rows of elongated pockets, the pockets of each row being located end to end in spaced relation and being staggered with respect to the adjacent rows so as to bridge the spaces between the adjacent rows, and lath rods located outside the sheet and extending longitudinally along the rows of pockets and lengthwise over the elongated open sides of the pockets.

In testimony whereof, we affix our signatures.

JULIUS KAHN.

HERBERT E. WHITE.
